E. M. H. WEBB.
CONVERTIBLE GARMENT.
APPLICATION FILED FEB. 1, 1918.

Patented May 28, 1918.

UNITED STATES PATENT OFFICE.

ELLEN M. H. WEBB, OF NEW YORK, N. Y.

CONVERTIBLE GARMENT.

1,267,944.

Specification of Letters Patent. Patented May 28, 1918.

Application filed February 1, 1918. Serial No. 214,882.

To all whom it may concern:

Be it known that I, ELLEN M. H. WEBB, a subject of the King of Great Britain, and a resident of the city of New York, borough 5 of Manhattan, in the county and State of New York, have invented a new and Improved Convertible Garment, of which the following is a full, clear, and exact description.

10 The invention relates to wearing apparel, and its object is to provide a new and improved convertible garment combining a dress and overalls more especially designed for the use of children, and arranged to 15 permit of conveniently and quickly converting the dress into overalls or vice versa, thus allowing a child to walk to and from a playground fully and cleanly dressed and to permit the child while on the playground 20 to play while being dressed in the overalls and with the dress protected from being soiled.

In order to accomplish the desired result, use is made of a dress and overalls, of 25 which either is adapted to be worn outside of the other, the overalls having shoulder straps connecting the back and front of the overalls with each other, fastening devices detachably connecting the back of the overalls with the back of the dress, and fastening devices detachably connecting the front of the overalls with the front of the dress. Use is also made of overall legs having their 30 lower portions adapted to be turned up 35 within the upper portion of the legs, and fastening members for securing the turned-up lower leg portions to the upper leg portions.

A practical embodiment of the invention 40 is represented in the accompanying drawings forming a part of this specification, in which similar characters of reference indicate corresponding parts in all the views.

Figure 1 is a front elevation of the garment 45 with the dress outside of the overalls and with one of the shoulder straps being disconnected from the front of the dress;

Fig. 2 is a rear elevation of the garment with the dress on the outside of the overalls, 50 parts being shown in section;

Fig. 3 is a front elevation of the garment

with the overalls outside of the dress and with one of the shoulder straps of the overalls disconnected from the corresponding front of the overalls;

55

Fig. 4 is a rear elevation of the garment with the overalls outside of the dress and with parts disconnected and parts shown in section;

Fig. 5 is an enlarged cross section of the 60 garment on the line 5—5 of Fig. 1;

Fig. 6 is a similar view of the same on the line 6—6 of Fig. 2;

Fig. 7 is a similar view of the same on the line 7—7 of Fig. 3; and

65

Fig. 8 is a similar view of the same on the line 8—8 of Fig. 4.

The convertible garment consists essentially of a child's dress 10 and overalls 11, either of which can be worn on the outside 70 of the other, as will be readily understood by comparison of Figs. 1 and 2 with Figs. 3 and 4. The dress 10 comprises the usual body 12 having sleeves 13 and a neck opening 14 with a front extension 15 adapted to 75 be closed by suitable fastening devices 16 after the dress is placed in position on the child's body. The dress is also ornamented with a belt 17 but this feature may be varied or entirely omitted, if desired. The dress 80 10 is provided at the front upper portion with buttonholes 18 disposed on opposite sides of the median line of the front of the dress, and directly above the buttonholes 18 are arranged slits 19. Similar buttonholes 85 20 are arranged on the back upper portion of the dress 12 and are disposed on opposite sides of the median line of the back of the dress, as plainly shown in Fig. 4, and directly above the buttonholes 20 are arranged 90 slits 21.

The overalls 11 comprise a body 25 from which extend legs 26, and a bib 27 provided with side flaps 28 having buttonholes 29 at their upper pointed ends. The body 25 is 95 also provided with a back 30 terminating in upwardly extending side flaps 31 to which are rigidly secured the rear ends of shoulder straps 32 provided at their forward ends with buttons 33. Buttons 34 are secured to 100 the outer faces of the flaps 31 at the junction of the shoulder straps 32 with the said

flaps 31, and on the back of the shoulder straps at this point are secured buttons 35. The lower portions of the legs 27 are adapted to be turned up to extend within the upper portions of the legs, and suitable fastening devices such as snap buttons are used for holding the lower portions of the legs in position in the upper portions of the legs at the time the garment is worn with the dress 10 on the outside of the overalls 11, as indicated in Figs. 1 and 2. The fastening devices are preferably in the form of sockets 40 attached to the inner sides of the lower portions of the legs and are adapted to engage studs 41 arranged on the inner sides of the upper ends of the legs, as plainly indicated in Fig. 4. When the overalls are worn outside of the dress 10 the fastening members 40 and 41 are disconnected and the lower leg portions are extended, as plainly indicated in Figs. 3 and 4.

When the child is to go to and from a playground the overalls 11 are arranged within the dress 10, as shown in Figs. 1 and 2, and with the lower portions of the legs 26 turned up within the upper portions thereof and fastened in place by the fastening devices 40 and 41. The buttons 33 of the shoulder straps 32 are engaged with the buttonholes 29 and 18 and the pointed ends of the flaps 28 project through the slits 19, as shown in Fig. 1. The buttons 34 are engaged with the buttonholes 20 and the pointed ends of the back flaps 31 project through the slits 21, as shown in Fig. 2. By the arrangement described the overalls are firmly attached both at the front and the back to the body 12 with the usual straps extending within the corresponding shoulder portions of the dress 10. When the child arrives at the playground the garment is converted so that the overalls 11 are outside of the dress 10, as shown in Figs. 3 and 4. For this purpose the nurse or other attendant of the child disconnects the buttons 33 and 34 from the corresponding buttonholes 18 and 20 and disengages the buttons 33 from the buttonholes 29 thus disconnecting the bib 27 from the back 30 of the overalls. The bib 27 and the back 30 of the overalls are pulled downward and the body 12 of the dress is now passed inside of the body 25 of the overalls, after which the shoulder straps 32 are passed up over the outside of the shoulders of the dress 10, and the free ends are passed into the slits 19 (see Fig. 7) after which the buttons 33 are passed through the buttonholes 18 and engage with the buttonholes 29 thus fastening the front of the overalls to the front of the dress. The extra button 35 previously mentioned is engaged with the buttonholes 20 (see Fig. 8) at the back of the garment to connect the back of the overalls with the back of the dress thus securely fastening the

overalls and dress together to prevent slipping of the shoulder straps 32 on the shoulders of the dress. The legs are now extended as previously described and shown in Figs. 3 and 4 thereby confining the lower portion of the dress body 12 within the body 25 of the overalls. The child is now dressed with the overalls outside of the dress 10. After play the garment is again converted with the dress 10 outside of the overalls, it being understood that for this purpose the buttons 33 are disengaged from the buttonholes 29 and 18 to allow of lowering the bib 27 and the back 30, after which the lower portion of the body 12 of the dress 10 is pulled out of the body 25 of the overalls 11 and passed over the bib 27 and the back 30, after which the shoulder straps 32 are again passed over the child's shoulders inside of the dress 10 and buttoned to the bib flaps 28 by engaging buttons 33 and buttonholes 29. The buttons 33 and 34 are now again connected with the buttonholes 18 and 20 and the terminals of the flaps 28 are projected through the slits 19 and the terminals of the flaps 31 are projected through the slits 21, as shown in Figs. 1 and 2. The lower portions of the legs 26 are now turned up with the upper portions thereof fastened in place by the fastening members 40 and 41, as previously described. The child is now dressed with the dress 10 on the outside and as this dress was protected by the overalls during the time the child was at the playground it is evident that the dress is not soiled and the child can walk home cleanly dressed.

It will be noticed that the dress and the overalls can be entirely disconnected one from the other to allow of cleaning whenever it is desired to do so.

Having thus described my invention, I claim as new and desire to secure by Letters Patent:

1. A convertible garment, comprising a dress and overalls, of which either is adapted to be worn outside of the other, the overalls having shoulder straps connecting the back and front of the overalls with each other, fastening devices detachably connecting the back of the overalls with the back of the dress, and fastening devices detachably connecting the front of the overalls with the front of the dress.

2. A convertible garment, comprising a dress and overalls, of which either is adapted to be worn outside of the other, the overalls having shoulder straps connecting the back and front of the overalls with each other, the overalls having the lower portions of the legs adapted to be turned up within the upper portions of the legs and fastened thereto, fastening devices detachably connecting the back of the overalls with the back of the dress, and fastening devices

detachably connecting the front of the overalls with the front of the dress.

3. A convertible garment, comprising a dress and overalls, the dress being provided at the front and back with buttonholes disposed at opposite sides of the median line of the front and back, the said overalls hav-

ing shoulder straps attached to the back and adapted to be buttoned to the front and to be engaged with the said front buttonholes, and buttons on the rear ends of the shoulder straps and adapted to engage the said back buttonholes. 10

ELLEN M. H. WEBB.
